UNITED STATES PATENT OFFICE.

WILLIAM DUNCAN, OF KEARNY, NEW JERSEY, ASSIGNOR, BY MESNE ASSIGNMENTS, TO THE AMERICAN METAL LATH FIREPROOF CONSTRUCTION AND MANUFACTURING COMPANY, OF NEWARK, NEW JERSEY.

MACHINE FOR MAKING EXPANDED METAL LATHING.

SPECIFICATION forming part of Letters Patent No. 639,157, dated December 12, 1899.

Application filed February 12, 1898. Serial No. 670,135. (No model.)

To all whom it may concern:

Be it known that I, WILLIAM DUNCAN, a citizen of the United States, residing at Kearny, in the county of Hudson and State of New Jersey, have invented certain new and useful Improvements in Machines for Making Expanded Metallic Lathing, of which the following is a full, clear, and exact description, such as will enable those skilled in the art to which it appertains to make and use the same, reference being had to the accompanying drawings, which form a part of this specification.

This invention relates to improvements in machines for making expanded metallic lathing, and more particularly in machines for making a lathing such as is disclosed in Patent No. 557,658, granted April 7, 1896. The lathing disclosed in the said patent consists, primarily, of a metallic plate provided with rows of angular slits breaking joint and expanded to throw keys from opposite sides of the plate. While the invention will be described in an embodiment adapted to make such a lathing, yet it can be used to make other lathing. For an instance, it is well adapted to make a lathing having straight instead of angular slits.

The invention has further for its object certain improvements in the machine disclosed in Patent No. 594,172, granted November 23, 1897. The device shown in the latter patent has certain defects which it is sought to eliminate in the invention in the present instance. In the device of the patent the dies cut a double row of slits and expand the ribs thereby formed practically simultaneously. This treatment of the metal concentrates certain strains on particular points of the metal and has thereby a tendency to tear the metal. The points where the strains are concentrated are near the ends of the slits. In the invention in the present instance this objectionable feature is eliminated.

The device in the present instance does not simultaneously cut and expand the metal to form the double row of keys. Its action is progressive, and thereby the strains on the metal are not concentrated, but are distributed, so that the tendency to tear is obviated. The invention in the present instance con-

sists, primarily, of a moving member in which a die is mounted consisting of a double row of fixed cutters and expanders, of a stationary member in which one of the rows of cutters and expanders is fixed and the other row 55 movable relative to the fixed row, and of a mechanism for operating the movable row, so that the latter is held in a position to perform its function in slitting the metal and then moved to allow the fixed row to successively 60 perform its function in cutting the second row of slits and then moved further to allow the slitted metal to be expanded by a further engagement of the cutters and expanders of both members. 65

The invention further consists in the novel construction, combination, and arrangement of parts, such as will be hereinafter fully described, pointed out in the appended claims, and illustrated in the accompanying drawings. 70

In the accompanying drawings, in which similar letters of reference designate corresponding parts, Figure 1 is a transverse vertical section on the line 11 of Fig. 2, showing 75 the members separated. Fig. 2 is a front elevation, partly in section, of a machine embodying the invention. Fig. 3 is a side elevation. Fig. 4 is a rear elevation, partly in section. Fig. 5 is a view similar to that shown 80 in Fig. 1, except that in this instance the members are closed. Fig. 6 is a detail view showing the cutters of the upper member. Fig. 7 is a similar view showing the cutters of the lower member. Fig. 8 is a plan view of a section of lathing made by the machine. 85

Referring to the drawings by letter, A designates the side frames of any construction suitable in the premises. The said frames are connected and held in position by the rods 90 A'. In each side frame a vertical guide A² is formed. A cross-head A³ is mounted at its ends in said guides. Secured to the cross-head is the upper member of the dies. Projecting from the ends of the cross-head are 95 wrist-pins A⁴. Pitmen A⁵, having their lower ends eccentrically journaled on the main driving-shaft A⁶ and their upper ends journaled on said wrist-pins, reciprocate the said cross-head. The dies A⁷, mounted in the lower 100

end of the cross-head, are of the same construction as those shown in Patent No. 594,172 before mentioned.

The stationary table B is secured to the side frames A in any suitable manner. To the back of said table are secured the fixed cutters B' of the lower member of the forming mechanism. The said cutters are mounted in the holder B², and the latter is adjustably secured in place by the bolts B³.

In the side frames A, below the table, guides B⁴ are formed, in which is mounted the support B⁵, carrying the movable cutters B⁶. The latter are mounted in the holder B⁷ and are secured therein by the screws B⁸. The support B⁵ is reciprocated by the cams B⁹, mounted on the main driving-shaft. The said cams engage with the shoes B¹⁰, adjustably secured to the support by the screws B¹¹, and thereby move the support. By adjusting the shoes the movement of the support by the cams can be regulated.

Feed-rolls C and C' are mounted in front of the forming mechanism. They are journaled at their ends in the side frames and are provided with means for intermittently moving them so that the metal will be fed forward during the separation of the dies. Secured on the lower roll is a ratchet-wheel C², with which a pawl C⁴ engages. A bell-crank C³ is pivoted on the shaft of the lower roll and carries the pawl. The bell-crank is oscillated by the pitman C⁵, with one end of which it is connected. The other end of the pitman is journaled on the wrist-pin C⁶, adjustably mounted in a slot formed in the end of the main driving-shaft A⁶. By adjusting the wrist-pin the movement of the feed-rolls can be regulated. Motion is carried from the lower feed-roll to the upper by intermeshing gear mounted on the ends of the shafts of the rolls farthest from the ratchet-wheel C².

The gripper mechanism consists of the angular foot D, extending the width of the machine. The said foot is held in place by two or more rods D'. In this instance only two are shown. The lower end of each rod passes through the shoe and registers with a hole D² in the table B. Its upper end passes through the bushing D³, carried by the bracket D⁴, projecting from the cross-head A³. A spring D⁵ is interposed between the under face of the shoe and the bottom of the recess D⁶. This spring serves to normally hold the shoe in an elevated position clear of the table. Between the upper face of the shoe and the bushing D³ is another spring D⁷. The object of the latter spring is when pressed upon by the bushing moved by the descent of the cross-head to press the shoe upon the plate introduced between the members of the forming mechanism and to hold the plate in place while the dies are in operation. It is obvious that the spring D⁷ must be considerably stronger than the spring D⁵, as the latter must be compressed to move the shoe toward the table.

A mechanism is mounted in the rear of the forming mechanism to carry away the lathing. Two guides E lead from the dies to the 70 rubber-covered rolls E'. The latter serve to carry the lathing from the machine. By being covered with rubber the rolls cannot injure the projecting keys of the lathing. The rolls are driven by a train of gears leading 75 from a gear on the lower of the feeding-in rolls to a gear mounted on the lower of the said carrying-away rolls.

In the process of making the lathing the metal is expanded so that its superficial area 80 after its leaves the dies is greatly increased. This increase varies with the character and quality of the metal. Under some conditions this increase is one hundred per cent. or more. Consequently the lathing travels faster in 85 leaving the machine than the plate does in entering. Therefore the peripheral speed of the carrying-away rolls E' must be greater than the peripheral speed of the feeding-in rolls. This is accomplished by means of suitable gearing or by making the diameters of the carrying-away rolls greater than those of the feeding-in rolls.

The operation of the device is as follows: After the machine has been started a blank 95 sheet of metal is introduced between the feeding-in rolls. The latter intermittently feed the plate forward between the members of the forming mechanism. The cross-head descends and the gripper mechanism grasps the 100 plate and holds it firmly. The rear row of cutters in the cross-head cut the first row of slits operating with the movable cutters in the lower member. Then the movable cutters are released by the cams and drop. The front 105 row of cutters in the cross-head then operates with the fixed row of cutters in the lower member to cut the second row of slits breaking joint with the first row of slits. As the cross-head moves downward and as the lower 110 movable cutters have come to a rest, the ribs formed by slitting the metal, owing to the shape of the dies, are expanded. The cross-head is then raised by the operating mechanism, and the intermittently-operated feed- 115 rolls and carrying-away rolls draw the plate into and the lathing out of the machine. This operation is repeated until the entire plate has passed through the dies.

The hereinbefore-described embodiment of 120 the invention is the preferred one, yet it can be departed from to a considerable extent without departing from the spirit of the invention.

Having thus described the invention, what 125 I claim, and desire to secure by Letters Patent, is—

1. In a machine for making expanded metallic lathing, a die consisting of a double row of cutters, one of the said rows of cutters 130 being movable relatively to the other row, and a second die co-operating with the first-mentioned die and having a row of cutters adapted to engage with and to move with said

- movable row of cutters of the first-mentioned die.
2. In a machine for making expanded metallic lathing, the combination of a moving member, a double row of cutters carried by said moving member, a fixed member, a row of immovable cutters mounted in said fixed member, and a row of movable cutters mounted in said fixed member adjacent to said row of immovable cutters.
3. In a machine for making expanded metallic lathing, the combination of a moving member, a double row of cutters carried by said moving members, a fixed member, a row of immovable cutters mounted in said fixed member adjacent to said immovable cutters, and means for intermittently moving said movable cutters mounted in the fixed member.
4. In a machine for making expanded metallic lathing, the combination of a support, a row of immovable cutters mounted in said support, a row of movable cutters mounted in said support adjacent to said immovable cutters, means for moving said movable cutters to vary the relative positions of said immovable and movable cutters, and a cutting mechanism coöperating with said cutters.
5. In a machine for making expanded metallic lathing, the combination of a support, an adjustable holder carried by said support, cutters mounted in said holder and adapted to be held immovable thereby, a row of movable cutters mounted in said support adjacent to said immovable cutters, means for moving said movable cutters, and a cutting mechanism coöperating with said cutters.
6. In a machine for making expanded metallic lathing, the combination of a support, a row of immovable cutters mounted in said support, a movable holder carried by said support, a row of cutters mounted in said holder, means for intermittently moving said holder, and a cutting mechanism coöperating with said cutters.
7. In a machine for making expanded metallic lathing, the combination of a support, an adjustable holder carried by said support, cutters mounted in said adjustable holder and adapted to be held stationary thereby, a mov-
- able holder carried by said support, cutters mounted in said movable holder, means for intermittently moving said movable holder, and a cutting mechanism coöperating with said cutters.
8. In a machine for making expanded metallic lathing, the combination of a support, a row of immovable cutters mounted in said support, a movable holder carried by said support, a row of cutters mounted in said holder, a cam mechanism for intermittently moving said holder, and a cutting mechanism coöperating with said cutters.
9. In a machine for making expanded metallic lathing, the combination of a support, a row of immovable cutters mounted in said support, a movable holder carried by said support, a row of cutters mounted in said holder, an adjustable shoe carried by said holder, a rotatable cam adapted to engage with said shoe, and a cutting mechanism coöperating with said cutters.
10. In a machine for making expanded metallic lathing, the combination of a die consisting of a double row of fixed cutters, and a second die coöperating with the first-mentioned die consisting of a row of fixed cutters and a row of movable cutters.
11. In a machine for making expanded metallic lathing, the combination of a die having a row of cutters, a second die coöperating with the first-mentioned die provided with a row of movable cutters adapted to yield to and move with the first-mentioned cutters on the coming together of the dies, and means for regulating the movement of the said movable cutters.
12. In a machine for making expanded metallic lathing, the combination of a die consisting of a double row of cutters, and a second die coöperating with the first-mentioned die consisting of a double row of cutters, one of the rows of cutters of the second die being movable independently of the other row.

In testimony whereof I hereunto affix my signature in the presence of two witnesses.

WILLIAM DUNCAN.
